UNITED STATES PATENT OFFICE.

FRED E. RAMSDEN, OF CHEROKEE, IOWA, ASSIGNOR TO CHARLES A. ERSKINE,
E. D. HUXFORD, AND JERRY D. ANDERSON, OF SAME PLACE.

WINDOW-SCREEN.

SPECIFICATION forming part of Letters Patent No. 551,095, dated December 10, 1895.

Application filed May 10, 1895. Serial No. 548,854. (No model.)

To all whom it may concern:

Be it known that I, FRED E. RAMSDEN, a citizen of the United States, residing at Cherokee, in the county of Cherokee and State of 5 Iowa, have invented a new and useful Improvement in Window-Screens, of which the following is a specification.

My invention relates to an improvement in window-screens, in which the frame, or any 10 frame whatever, commonly used in screening windows with what is commonly known as "wire screening" is entirely done away with and abandoned.

The object of my invention is to furnish a 15 way in which to screen a window of any size or dimensions with wire or any other strong and durable screening in a quick, easy, durable, and cheap manner. I attain this object by the mechanism illustrated in the accompanying drawing, in which—

A and B represent, each, a slat or stick of wood made in proportions to the width and size of the window to be screened. At the top of A is tacked the upper edge of the wire 25 screening G, and at the lower edge of B is tacked the lower edge of the screen G. At the letters C, D, E, and F are screwed to the window-frame a small bracket L, shaped at an angle of ninety degrees, or better if a trifle 30 over ninety degrees, so that when the tension of the screen is increased it will have a tendency to bring the sticks tighter against the window-frame. The stick B is placed closely against the window-sill and the brackets E 35 and F are screwed to the casing just above

the ends of the stick B, as shown in the drawing. At C and D are placed two brackets similar in shape to E and F and screwed firmly to the window-casing at a distance below the top of the window sufficient to allow 40 the stick A to be placed above them and to cover the entire window to be screened. Through the upper part of the brackets C and D is a threaded hole, and through these threaded holes is passed a thumb-screw, which when 45 tightened is forced against the lower edge of the stick A and thus tightens the screen G firmly over and across the window-opening. The tension of the wire screening may thus be regulated by the thumb-screws in the 50 brackets at C and D.

From this combination of the two sticks of wood A and B and the brackets C, D, E, and F and thumb-screws at C and D and use of screen, 55

I claim—

In combination with the window frame, the screen, the top and bottom boards A, B, projecting beyond the screen and having said screen attached thereto on their inner sides, 60 the right angular brackets E, F, under which the lower board B fits and the upper brackets C, D, said upper brackets having the adjusting screws to bear on the upper board, substantially as described.

FRED E. RAMSDEN.
